BELL

Filed May 17, 1949

UNITED STATES PATENT OFFICE

2,584,223

BELL

Frank Petelinsek, Milwaukee, Wis.

Application May 17, 1949, Serial No. 93,781

2 Claims. (Cl. 116—150)

1

This invention relates to a bell, and more particularly to the formation of a novel bell for use as an ornamental or decorative device.

It is an object of this invention to provide a novel bell of the kind to be more particularly described hereinafter, which is particularly formed for rapid fabrication and assembly with a minimum of labor and tools.

Another object of this invention is to provide a bell of this kind which is pleasing in appearance and sound and formed for securely engaging the tongue, link and hammer to the head of the bell to prevent their accidental displacement or disengagement. The bell is formed for the secure fastening of the link thereto after the link, tongue and hammer are assembled. The disposition of the link in relation to the head of the bell provides for the secure support of the ball, wherein the body of the bell and the tongue are separately secured to the link.

With the above and other objects in view, my invention consists in the arrangement, combination and details of construction disclosed in the drawings and specification, and then more particularly pointed out in the appended claims.

In the drawings:

Figure 1 is a side elevation of a bell constructed according to an embodiment of my invention;

Figure 2 is a top plan view thereof;

Figure 3 is a transverse section taken on the line 3—3 of Figure 1;

Figure 4 is a fragmentary transverse section taken through the bell link and clapper, taken on the line 4—4 of Figure 3;

Figure 5 is a fragmentary transverse section of the upper end or head of the bell body, showing the lugs in their dependent initial position prior to their engagement in the restricted neck of the link.

Referring to the drawings, the numeral 10 designates generally a novel bell formed according to an embodiment of my invention. The bell 10 is preferably formed of metal or other suitable resonant material and is preferably formed of a size to be used particularly as a decorative or ornamental article.

The bell 10 is formed of a hollow bell body 11 open at the bottom thereof and having downwardly and outwardly-flared side walls 12. A head 14 on the upper end of the side walls 12 substantially closes the upper end of the bell body 11, and a peripheral or marginal flange 15 is formed on the extreme lower edges of the side walls.

The annular flange 15 is preferably formed in

the initial formation of the bell body 11, the flange 15 extending substantially concentric to the axis of the body 11, being spaced outwardly therefrom as a continuation of the lower edges of the side walls 12. As the flange 15 is preferably formed in the formation of the bell body 11, the flange 15 will be of a reduced cross-section, as compared to the thickness of the side walls 12, to add to the ornamental appearance of the bell as viewed from the lower open end.

The head 14 is formed with a transverse slot 17 extending thereacross. The slot 17 extends diametrically across the upper end or head 14 of the body 11 and is formed for receiving therein a link 18.

At the opposite ends of the slot 17, a pair of inwardly-extending, confronting lugs 19 are formed integrally with the head 14 and extend inwardly from the opposite ends of the slot. The lugs 19 are preferably formed in the initial casting or formation of the body 11 and in their initial formation the lugs 19 will preferably extend downwardly and inwardly within the body 11 in the manner as clearly shown in Figure 5 of the drawings. The side edges of the lugs 19 are separated from the opposite longitudinal side walls of the slot 17 to provide for the later bending or deformation of the lugs 19 to shorten the slot 17 and to provide shoulders for engagement by the link 18 to secure the link in the head of the bell body 11.

The link 18 is formed of a short length of flat metal having a general width substantially greater than the length of the slot 17. The link 18 comprises an upper loop 20 having a central opening 21, and a lower plate 22 which is generally polygonal in configuration, having downwardly converging side edges 24 and 25 and an arcuate lower edge 26. A circular opening 27 is formed at the lower end of the plate 22 substantially providing a lower link connected to the upper link 18. The upper ends of the edges of the plate 22 terminate in laterally inwardly, slightly inclined shoulders 28 and 29, whose inward ends meet the sides of the loop 20 at the lower end of the loop 20 and define notches or recesses 30 and 31 at the connecting point of the loop 20 and plate 22 which are substantially wider than the thickness of the lugs 19.

The lugs 19 at the opposite ends of the slot 17 are adapted to be bent upwardly from their initial position for engagement in the oppositely-disposed recesses 30 and 31 on the opposite side edges of the link 18 for loosely securing the link 18 in the bell body 11.

A tongue 34 is swingably connected to the

lower end of the link 18, the tongue 24 formed of a flat stamped strip of metal formed to define an open ring 35 at the upper end thereof, passed through the link opening 27, having arms 36 and 37 extending downwardly from the ends of the ring 35. The arms 36 and 37 normally are in overlying relation to each other, as shown in Figure 4 of the drawings. The extreme lower ends of the respective arms 36 and 37 are out-turned to define lugs 38 and 39.

The hammer 40 is a solid, spherical body 41 formed of metal or other suitable material. The body 41 is formed with a peripheral reinforcing bead 42 about the horizontal diameter thereof and with a socket 44 in its top. The lower ends of the arms 36 and 37 are inserted in the socket 44, the body 41 being thereafter swaged, stamped, or otherwise deformed to secure the lower ends of the arms 36 and 37 and their lugs 38 and 39 in the socket 44. Together the tongue 34 and hammer 40 constitute a clapper swingably mounted on the lower end of the link 18.

In the initial formation of the bell 10, the body 11 is initially cast or otherwise formed with the lugs 19 extending downwardly and inwardly from the opposite ends of the slot 17. The clapper 47 is then engaged on the link 18 by initially separating the arms 36 and 37 and extending one of the arms through the opening 27 and returning the arms to their overlying relation and applying the hammer 40. The loop 26 being larger in diameter than the distance between the lugs 19, the sides of the loop rest thereon. Upon upward movement of the link 18 relative to the bell body 11 the shoulders 28 and 29 engage the underside of the lugs 19, the width of the notches 30, 31 permitting some free vertical movement of the link 18 relative to the bell body 11 between the extremes indicated.

The loop 20 provides for the attachment of the bell to any suitable supporting device, as a chain or cord, or other attaching means for securing the bell 10 to a garment, purse, or other article.

I do not mean to confine myself to the exact details of construction herein disclosed, but claim all variations falling within the purview of the appended claims.

I claim:

1. In a bell, a hollow bell body, a head closing the upper end of said body, said head being formed with a transverse slot extending therethrough, a link comprising a plate having a loop on its upper end larger in diameter than said slot whereby opposite sides of the lower end of the loop can rest upon said head at the opposite ends of the slot, an intermediate portion depending from said loop, said intermediate part being narrower than the length of the slot and depending loosely through the slot, and a lower plate portion depending from said intermediate portion, the upper end of said plate portion being wider than said intermediate portion and wider than the length of the slot, said upper end of said plate portions having shoulders on op-

posite sides thereof engageable with the underside of said head, and a tongue pivotally connected to the lower end of said link having a hammer on its lower end, said shoulders being spaced below the lower end of said loop at a distance greater than the thickness of said head whereby limited free vertical movement of said link relative to said head is provided for, said head having lugs at the ends of the slot, said lugs being initially deflected out of the slot to permit insertion of the loop of said link into the slot and subsequently deflected to extend longitudinally into the slot so as to reduce the effective length of the slot and act as means in conjunction with said shoulders and the lower end of said loop for retaining the link assembled to the bell body.

2. In a bell, a hollow bell body, a head closing the upper end of said body, said head being provided with a closed slot arranged transversely thereof and extending therethrough, deformable opposed lugs on the end walls of said slot, a link comprising a plate having a loop on its upper end arranged exteriorly of said head and having its lower end portion extending slidably through said slot and supportable upon the opposed lugs, an intermediate portion depending from the lower end portion of said loop and slidably loosely through said slot, and a lower plate portion positioned within said bell body and dependently supported from said intermediate portion, the upper end of said lower plate portion being wider than the length of said slot and engageable with said lugs, a tongue arranged within said bell body below said lower plate portion and having one end pivotally and dependently connected to said lower plate portion, and a hammer dependently carried by the other end of said tongue and engageable with the inner surface of said hollow bell body, said lugs being initially deflected out of the slot to permit insertion of the loop of said link into the slot and subsequently deflected to extend longitudinally into the slot so as to reduce the effective length of the slot and act as means in conjunction with the upper end of the plate portion of said link and the lower end of the loop of said link for retaining the link assembled to the bell body.

FRANK PETELINSEK.
